UNITED STATES PATENT OFFICE.

EDWARD HARRALSON, OF MEMPHIS, TENNESSEE.

COIN-ASSORTER.

1,076,113.

Specification of Letters Patent.

Patented Oct. 21, 1913.

Application filed June 8, 1912. Serial No. 702,449.

To all whom it may concern:

Be it known that I, EDWARD HARRALSON, a citizen of the United States, residing at Memphis, county of Shelby, and State of Tennessee, have invented certain new and useful Improvements in Coin-Assorters, of which the following is a specification.

This invention relates to coin assorters.

My object is to provide a machine of simple, light and durable construction adapted for rapidly and accurately assorting coins of all denominations, and it may comprise one, or a plurality of traveling assorting coin conveyers arranged one below the other, and combined with a surface or chute, the assorting conveyer or conveyers being provided with coin holders of such sizes, beginning with the uppermost coin assorter, that the largest coins will be caught by the uppermost holders, the next to the largest by the next series of holders therebelow and so on to the lowermost assorter, whereby an aggregation of coins may be introduced into the machine and will automatically classify themselves by gravity and be arrested by the coin assorters designed to catch and carry them to a suitable point of discharge. Suitable coin counters may be used in connection with any or all of the coin assorters and any desired means employed for collecting the coins after they have been assorted. Preferably, the coin conveyer or conveyers are endless, provided with projecting lugs or pins to arrest the coins intended to be engaged thereby, and the chute or gravity surface provided with slots in which the pins travel. Any suitable operating means may be employed for causing the conveyers to move, but preferably, where a plurality of conveyers are employed, an operating means common to all will be used, whereby they will be simultaneously operated.

The invention further comprises coin releasers arranged to prevent smaller coins from being carried off by engagement with larger coins and, still further, in the provision of coin guides for directing the coins to the coin-holding spaces of the respective coin conveyers, whereby the guidance of coins of the proper denominations to their respective conveyers is insured. Preferably, a guiding front, properly spaced apart from the chute or gravity surface, is provided, to

prevent any tilting of the coins or the passage thereof beyond the conveyer which is designed to carry coins of that particular denomination from the machine.

The invention is susceptible of various modifications without departing from the spirit and scope thereof and I lay claim to all changes coming within the purview of the invention, one embodiment of which is disclosed in the accompanying drawings, in which—

Figure 1 is a perspective of the complete machine; Fig. 2, a horizontal section thereof; Fig. 3, a detail perspective of parts of one of the coin assorting conveyers; Fig. 4, a vertical section of the machine; Fig. 5, a side elevation of the delivery side of the machine; Fig. 6, a horizontal detail section showing one of the conveyers in full lines; Fig. 7, a detail view showing how but one coin releaser may be employed; and Fig. 8, a similar view showing a plurality of coin releasers and chutes.

The operative parts are supported by a frame 1 preferably contained within a casing 2 of suitable design. The frame 1 has a front which is inclined.

Secured to the frame 1 in any suitable or preferred manner is a series of plates 3, preferably of sheet steel, which are separated from each other by slots 4 and all of which lie in the same plane constituting, as a whole, an inclined surface or chute down which the coins travel. Spaced from the respective plates 3 are outer plates 5 corresponding, or substantially so, to the plates 3 and suitably mounted on the frame or constituting a part of the case. As appears from Fig. 1, these outer plates 5 may be of glass and constitute a transparent front through which the movements of the coins may be observed, and as shown in Fig. 4, the outer plates 5 are spaced farthest from the uppermost plates 3 and, in order, nearer to the plates 3, considering the plates 3 from the uppermost one to the lowermost one thereof. The object of this peculiar spacing of the plates 5 from the plates 3 is to provide a space between plates 3 and 5 just a little greater than the thickness of the coin. For instance, the uppermost plates 3 and 5 are spaced just far enough to accommodate silver dollars, the next plates 3 and

5 therebelow are spaced just far enough to accommodate silver half dollars, the succeeding plates 3 and 5 are spaced just far enough apart to accommodate quarter dollars and so on. This arrangement prevents the passage of coins below the point where they are to be sorted.

Suitably mounted on the frame 1 or the case 2, preferably the former, are shafts 6 and 7 which carry sprocket wheels 8 and 9. Gearing 10 connects the shaft 7 with a shaft 11 having a handle or crank 12 disposed outside the case 2. Engaged with the sprocket wheels 8 and 9 are a series of endless coin assorting conveyers 13, 14, 15, 16, 17 and 18 which are provided with points, pins or lugs 19 which project through the slots 4 and may be guided by the margins of said slots, the slots 4 being preferably only slightly wider than the thickness or diameter of the pins or lugs. Such construction insures the guidance of the coin assorting conveyers during their movements and prevents disengagement from their sprocket wheels or any sagging thereof. The coin assorting conveyers have one stretch or strand traveling beneath the plates 3, the lugs or pins 19 projecting between the slots. In addition to the construction described, other means may be employed for guiding the coin assorting conveyers. I am aware that these coin assorting conveyers and the means thereon for catching and classifying the coins are subject to modification and I do not, therefore, limit myself to details of construction in regard to them. They might be provided with parts projecting through the slots 4, such parts having transverse slots or recesses of a size adapted to retain the coin intended to be carried off and to permit smaller coins to pass through. The lugs or pins 19, it will be observed, provide a series of spaces or seats through which all coins, except those intended to be carried off by the particular conveyer, are adapted to pass.

I am aware that continuous belts or aprons having points or lugs could be substituted for sprocket chains and I lay claim thereto.

50 While I do not limit myself thereto, I prefer to construct the conveyers 13, 14, etc., of a series of chain blocks 20 provided with integral or inserted pins or lugs 19, the blocks being pivoted together at 22 and having openings 23 for the reception of the teeth of the sprocket wheels.

On the respective plates 3 there are provided coin releasers 24 having inclined faces 25. There may be a single coin releaser for each plate 3, as shown in Fig. 7, or, I may, preferably, provide on each plate 3 a series of spaced and inclined coin chutes 26, as shown in Fig. 8, whose purpose is to separate the coins which have passed through the coin assorting conveyer or conveyers

above and direct them to the spaces between the lugs or pins of the conveyer below. This facilitates the distribution of the coins and they also serve to dislodge any smaller coins which have been caught between coins of a larger denomination that have been arrested by the particular coin conveyer and are being carried off laterally thereby.

At the upper part of the machine there is a hopper 27 into which coins of all denominations may be indiscriminately deposited. If, now, the crank or handle 12 be turned, the coin assorting conveyers 13, 14, 15, 16, 17 and 18 will be made to travel simultaneously. The largest coins, such as silver dollars are arrested by the lugs or holders 19 on the uppermost conveyer 13, all other coins sliding between the lugs and down the chute or inclined surface composed of the plates 3 and, according to their size, being arrested by the respective conveyers, the lowermost conveyer 18 catching dimes, for instance. The lugs or pins 19 of all conveyers above that designed to catch a particular coin are spaced apart distances sufficient to permit such smaller coins to pass therethrough. Smaller coins which have been arrested by larger coins on a conveyer, are released therefrom by the coin releasers 24, being brushed off from the coins on which they rest, due to the travel of the coin conveyers, and then falling through unoccupied spaces on the same coin conveyer. Regardless of how many times smaller coins may be thus arrested, they eventually pass by gravity to the coin conveyer designed to catch them.

Any desired counting means may be employed in connection with each conveyer for counting the number of coins of that denomination that are carried off by such conveyer and any desired receptacles may be provided to catch the coins as they issue from the slots 28 at the delivery side of the machine or any desired chutes or other means may be employed to carry the coins therefrom to any suitable point.

Having thus described my invention, what I claim as new and desire to secure by Letters Patent, is:

1. In a coin assorter, the combination with an inclined surface or chute, of coin assorting conveyers respectively provided with means for arresting coins of a given size and arranged to travel crosswise of the inclined surface or chute and so related thereto that coins which have not been arrested by a preceding conveyer may pass down said chute from one conveyer to a succeeding conveyer.

2. In a coin assorter, the combination with an inclined surface or chute, of coin assorting conveyers each having means adapted for the arrest of coins of a given size, the conveyers being arranged to travel crosswise of the inclined surface or chute and

disposed in succession and having their coin arresting means adapted, successively, to arrest coins of smaller sizes gravitating down said chute from one conveyer to a succeeding one.

3. A coin assorter having a plurality of traveling endless belt, apron, or chain coin assorting conveyers respectively provided with means for arresting coins of a given size and arranged for the passage from one coin conveyer to succeeding coin conveyers of coins not arrested by a preceding conveyer.

15 4. A coin assorter having a plurality of endless traveling coin conveyers respectively having means adapted to arrest coins of a given size, said conveyers being arranged in succession beginning with the uppermost conveyor adapted to arrest coins of the largest size and ending with the lowermost conveyor adapted to arrest coins of a smaller size, the conveyers being arranged to travel in a general lateral direction, and a gravity surface or chute coöperating with said endless conveyers adapted to pass the coins in succession to another.

5. In a coin assorter, the combination with an inclined surface or chute, of a plurality of traveling coin conveyers arranged in succession, each conveyer having members spaced apart a distance sufficient to permit the passage of all coins smaller in size than those designed to be arrested by said conveyer, the conveyers being arranged one above the other in relation to the same chute and coöoperating with said chute so that coins not caught by a preceding conveyer will pass down the said chute to a succeeding conveyer, and a gravity surface or chute with which the spaced members of all of the conveyers coöperate in sorting the coins.

6. In a coin assorter, the combination with a plurality of traveling coin conveyers arranged in succession, each conveyer having members spaced apart a distance sufficient to permit the passage of all coins smaller in size than those designed to be arrested by said conveyer, in combination with a coin conveying surface or chute having slots in which the members of the respective conveyers travel, and a gravity surface or chute with which the spaced members of all of the conveyers coöperate in sorting the coins.

7. A coin assorter having a plurality of traveling rows of freely projecting members, the rows being arranged in succession and the projecting members of the succeeding rows being spaced apart at different distances from the members of a preceding row, the respective rows being arranged for successive action on the coins.

8. A coin assorter having a plurality of traveling rows of projecting members, the rows being arranged in succession and the projecting members of the succeeding rows.

being spaced apart at different distances from the members of the preceding row, in combination with a coin chute or surface with which all of said rows of projecting members cooperate, said surface or chute being adapted for directing the coins to the rows of projecting members. 70

9. A coin assorter having a plurality of traveling rows of projecting members, the rows being arranged in succession and the projecting members of the succeeding rows being spaced apart at different distances from the members of a preceding row, and means for releasing or dislodging smaller coins caught by larger coins which have been arrested and are being carried off by a given row of projecting members. 75 80

10. A coin assorter having a plurality of traveling rows of projecting members, the rows being arranged in succession and the projecting members of the succeeding rows being spaced apart at different distances from the members of a preceding row, a coin chute or surface for directing the coins in succession to the respective rows of traveling projecting members and with which said projecting members coöperate, and means for dislodging or releasing smaller coins caught by larger coins which have been arrested and are being carried off by a given row of projecting members.

11. A coin assorter having a plurality of traveling rows of projecting members, the rows being arranged in succession and the projecting members of the succeeding rows 100 being spaced apart at different distances from the members of the preceding row, in combination with a surface or chute for directing the coins to the rows of traveling projecting members, and stationary combined 105 coin guides and releasers adapted for directing the coins to the rows of traveling projecting members and also for releasing or dislodging the smaller coins which have been caught by larger coins that have been 110 arrested by a row of traveling projecting members.

12. In a coin assorter, the combination with an inclined coin chute or surface composed of plates separated by slots, of endless coin assorting conveyers having projecting members traveling in said slots, the conveyers being arranged substantially parallel one above the other and the projecting members being graded in spacing from those of the uppermost conveyer which are the widest separated to those of the lowermost conveyer which are the closest together, a cover spaced apart from said coin chute or surface a distance sufficient to permit the passage of the coins without their tilting, and coin guides and releasers arranged above the respective coin conveyers. 115 120 125

13. In a coin assorter, the combination with a receptacle into which coins of vari- 130

ous denominations are deposited indiscriminately, of a shifting coin-assorting member toward which the indiscriminate coins are directed flatwise from said receptacle, said 5 coin-assorting member having seats arranged to catch coins of a particular denomination edgewise and carry them away in a flatwise position in relation to the receptacle.

14. In a coin assorster, the combination 10 with a receptacle into which coins of various denominations are deposited indiscriminately, of a shiftable coin-assorting member toward which the indiscriminate coins are directed flatwise from said receptacle, said 15 coin-assorting member having seats arranged to catch coins of a particular denomination edgewise and carry them away in a flatwise position in relation to the receptacle, said seats so arranged that coins of 20 smaller denominations may pass edgewise therethrough without being caught.

15. In a coin assorster, the combination 25 with a receptacle into which coins of various denominations are deposited indiscriminately, of a coin-assorting member toward which the indiscriminate coins are directed, said coin-assorting member being shiftable cross-wise of the receptacle and having seats to catch coins of a particular denomination 30 and carry them away from the remaining coins of other denominations, and a coin releaser to dislodge coins contacting those

coins resting in and being carried away by the seats.

16. A coin assorster comprising a receiving member into which coins of various denominations are deposited indiscriminately, a coin-assorting member, one of said members shiftable crosswise to the other, the coin-assorting member having seats to catch 40 coins of a particular denomination and a coin releaser to dislodge coins contacting those coins caught and being carried away by the seats.

17. In a coin assorting device, the combination with a chute having oppositely disposed members, between which the coins pass, of a plurality of series of assorting seats arranged to shift across the chute between the members, each series designed to 50 catch coins of a particular denomination and convey them from the chute, one of the members of the chute being so arranged relatively to the opposite member that the space between the members is successively 55 decreased to correspond with the decreasing thicknesses of the coins.

In testimony whereof, I hereunto affix my signature in presence of two witnesses.

EDWARD HARRALSON.
